CLAIM

The ornamental design for a vehicle tracking device, as shown and described.

DESCRIPTION

FIG. 1 is a front perspective view of a vehicle tracking device of the present design;

FIG. 2 is an additional front perspective view thereof;

FIG. 3 is an additional front perspective view thereof;

FIG. 4 is a top plan view thereof;

FIG. 5 is a bottom plan view thereof;

FIG. 6 is a side elevation view thereof;

FIG. 7 is another side elevation view thereof;

FIG. 8 is a front view thereof;

FIG. 9 is a rear view thereof;

FIG. 10 is a bottom plan view of a second embodiment of a vehicle tracking device; and,

FIG. 11 is a side elevation view thereof.

The broken lines shown in the drawings are for illustrative purposes only and form no part of the claimed design.
